Primary Examiner—Nelson C. Holtje*Assistant Examiner*—Jeffrey Asch*Attorney, Agent, or Firm*—Weingram & Zall[57] **CLAIM**

The ornamental design for a sound powered telephone handset, as shown and described.

DESCRIPTION

FIG. 1 is a perspective view of a sound powered telephone handset, showing my new design;

FIG. 2 is a side elevational view, the opposite side being identical thereto;

FIG. 3 is a top plan view;

FIG. 4 is a bottom plan view;

FIG. 5 is an end elevational view; and,

FIG. 6 is another end elevational view, opposite to the view in FIG. 5.

FIG. 1

FIG. 2

FIG. 3

FIG. 4

FIG. 5

FIG. 6
